UNITED STATES PATENT OFFICE

2,106,642

CIRCULATING HEATER

George D. Matthews, Chattanooga, Tenn., assignor to Tennessee Stove Works, Chattanooga, Tenn., a corporation of Tennessee

Application December 13, 1935, Serial No. 54,291

3 Claims. (Cl. 126—67)

My invention relates to circulating heaters, and more particularly to latches and openers, for stoves, furnaces and the like.

It has been the practice in the prior art of 5 stoves and especially circulating heaters to employ an outer and an inner casing and a door made of spaced inner and outer portions in the side of such casings and hinged thereto for permitting the insertion of coal or other fuel into 10 the inner casing. Ordinarily such a door is maintained in closed position by a securing means of such construction that a handle extending from the outer surface of the door may be rotated and may move an inner catch secured to the inner 15 surface of the door whereby it is wedged against the wall of the inner casing thereby holding the door in closed position. Examples of this type of construction are disclosed in Sperry, 1,644,900 and Simons, 1,713,782.

20 The disadvantage of this type of construction is that the wedge or latch is exposed to the fire where it may be decomposed or consumed by the excessive heat of such fire, so that very shortly it becomes ineffective as a latch and no longer 25 can serve to secure the door. Another disadvantage is occasioned by the necessity for using an outer handle adapted to be gripped by the hand and turned. The extension of such handle from 30 the door permits impact and contact with other objects thereby permitting it to be broken or injured to such an extent that it is in no condition to perform its proper functions after a very short usage. Furthermore after some usage this structure is no longer able to maintain the door 35 in tight closed position thereby permitting air to enter the stove. Each of these disadvantages contributes to a very unsatisfactory latch.

In the above type of construction one hand must be free to release the latch and then to 40 open the door. This is often very inconvenient especially when the party has a lump of coal in each hand.

45 With a knowledge of the disadvantages and defects in the prior art, I have as an object of my invention the use of a latch which will eliminate the element exposed to the fire to be eaten away, the elimination of a prominent handle subject to impacts and frequent breakage and the introduction of a latch which will maintain the 50 door in tight closed position at all times and in deference to the wear of parts whereby eliminating the ingress of air and creation of a draft due to looseness.

55 I have for a further object the use of a quickly and easily actuated latch which requires only

foot movement of its elements in order to insure its operation.

I have for a further object the introduction of a foot actuated means for releasing the latch and additional means for forcing the door to open 5 position after the latch has been released whereby the party is free at all times to transport coal in both hands without inconvenience.

It is a further object of my invention to provide a door which may be latched in position by 10 merely pushing it to closed position, and may be opened by pulling.

It is a still further object of my invention to employ a spring actuated latch for securing the 15 door or doors in closed position, and in positioning said spring where heat from the stove will not attack and effect its resilient properties.

In the prior art such patents as Schutz, 1,256, 934, disclose spring actuated latch means cooperating with beveled surfaced seats for maintaining 20 a door in closed and ever in sealed position. While such a latch might be conveniently used for large doors such as ice closures, it would be undesirable for small ones and especially for 25 stoves as manual means must be provided for releasing the latch and heat from the stove would destroy the resilient properties of the spring.

Foot actuated opening means for doors have been in use. The patents to Stevenson et al., 911,175 and Tower 533,571 have been employed 30 for large doors to rooms. However, they have no application to small structures such as stoves since radically different in structure from those necessary to meet the requirements of a stove or other device having a small door. Furthermore 35 the heat from the stove would destroy the resilient properties of the springs. There would be no place for the foot lever and no way of joining it to the latch for a stove.

Hunt, 1,694,686 discloses means operated by the 40 foot for releasing the latch but discloses neither a spring pressed latch nor means for opening the door after the latch has been released. Brewer, 720,399, discloses a means operated by a piston 45 and valve for opening a furnace door.

Although spring actuated latches and latch releasing means have been known, it is my belief that I have been the first to recognize that it would be possible and desirable to apply a latch 50 to a stove and to provide auxiliary means for cooperating with it to produce the above enumerated new and unexpected results.

Other objects and advantages of my invention will appear in the following specification, and 55

the novel features of the invention will be particularly pointed out in the annexed claims.

Figure 1 shows a perspective of a circulating heater, partly in section, employing the preferred embodiment of my invention. Figure 2 shows a plan view of a circulating heater incorporating the same form of my invention in it. Figure 3 is an enlargement of the lug showing its contour. Figure 4 is a perspective of a part of a circulating heater, partly in section, disclosing a modified form of my invention. Figure 5 is a perspective of part of a circulating heater, partly in section, disclosing a modified form of my invention. Figure 6 discloses a detail of my foot operating mechanism. Figure 7 discloses a plan view of a modified form of a door operating means.

In the drawings 1 designates an inner casing which forms a combustion chamber about one extremity of which a flange 2 extends around the entire outer surface and serves to space it from an outer enameled casing. A door 3 is secured to the inner casing and is comprised of two spaced parts, the inner being of the same material as the inner casing, and the outer coated with enamel. From the free end of the inner part of said door extends a lug 4 of such configuration that the top surface is flat and the lower part is formed of oppositely beveled surfaces 21, 22. To the inner casing is secured a pivot arm 6 upon one end of which a roller 5 is mounted. The bracket 7 positions the arm 6, and to the other end of the arm is secured a rod 9 through an opening in the transverse portion 8. The other end of said rod passes through a housing 10 secured to flange 2, in which housing is seated compression spring 11. A nut 12 is screw threaded to rod 9. The fuel door 3 is supported by a hinge 15 having an outstanding portion with an opening therein for the reception of an end of a rod 16 whose free end extends through the outer casing for insertion into a compression spring 17, and 18 designates a knob secured to rod 16 for maintaining spring 17 in normal slightly compressed condition. 19 designates a shoulder on casing 1 for preventing door 3 from being raised by the action of the latch arm 6. 20 represents a knob or handle on door 3 for opening, and 23, 24, 25, 26, 27, 28, 29, 30, and 31 designate a similar spring actuated latch system for the ash door of a circulating heater.

This form of my invention in its operation is somewhat as follows:

In opening the fuel door by hand, the party grasps knob 20 and pulls. This force moves the door outwardly by causing roller 5 to move over surface 21 rocking arm 6 downwardly, and rod 9 upwardly by causing spring 11 to be compressed to a greater degree. Upon reaching the end of surface 21 and the beginning of surface 22 the roller moves faster and kicks the door slightly for in moving up surface 22 the spring acts on rod 9 to rock arm 6 and move roller 5 up across the surface forcing the lug outwardly. After this no additional force is required to swing the door to open position for spring 17 expands, moving rod 16 through the opening in the outer casing carrying the outstanding portion 15 in the same direction, and swinging the door to open position.

The door is closed by merely pushing or slamming it. Upon reaching the latch, lug 4 is engaged by roller 5 on surface 22, and such roller

is forced downwardly as it rides over this surface, thus swinging arm 6 on its pivot, and raising rod 9 compressing spring 11. After this the roller passes on and rides upwardly on surface 21, spring 11 moves rod 9 downwardly and rocks arm 6 on its pivot thereby moving roller 5 as far along surface 21 as possible. However, movement of roller 5 along surface 21 is limited by the engagement of door 3 with casing 1, but the door is always urged to tight sealed position against casing 1 by the action of spring 11 acting through arm 6 and roller 5. Therefore, ingress of air at the door is always reduced to a minimum and the effectiveness of the seal is not destroyed by wear.

The operation of the latch for the ash door is similar to that employed for the fuel door above described.

When the hands of the party are not available for opening the fuel door, he may employ the foot to exert pressure upon the pivoted lever 13 which causes it to rock, and acting through nut or abutment 12 force lever 9 upwardly and move arm 6 about its pivot, thus moving roller 5 downwardly out of contact with lug 4 and removing the latch action. This leaves rod 16 and spring 17 free to force door 3 to open position, whereby fuel may be inserted. The foot is removed from the lever as soon as the lug 4 clears roller 5 and moves towards open position. The door is again closed in the manner above described.

Instead of using the door opening means of Figures 1 and 2, a modified form disclosed in Figure 7 may be employed. An extending lug 15' from the hinge may cooperate with rod 16' and be actuated by a tension spring 17' secured at one end to the inner wall of the outer casing and at the other to the free end of rod 16'. In this form spring 17' is always in expanded position and has a tendency to contract. As it contracts the lug 15' is moved and the door swung open.

In the modification of Figure 4 the roller 5' moves over the end of lug 4' on oppositely beveled surfaces to lock the door 3' in closed position. 6' designates the arm upon which roller 5' is mounted and said arm is in turn pivotally mounted upon a bracket 7' secured to casing 1'. The free end of arm 6' is secured to rod 9' whose free end is attached to a tension spring 11' on the inner wall of the outer casing. There is no provision made in this embodiment for a foot actuated release lever, however, it is recognized that a number of ways may be employed to release the latch by the foot. The door is opened by simply gripping the knob 20' in the hand and pulling it which forces the roller 5' to move back across the latch surface and release the lug. If desired a door opening means of the type disclosed in Figures 1 and 7 may be employed to swing the door to open position after the latch has been released.

In the modified form of Figure 5 is unnecessary to employ a lug or shoulder on the casing 1'' to prevent the fuel door 3'' from being forced up out of position by the action of the spring actuated arm 6''. Roller 5'', arm 6'', rod 9'' and foot lever 13'' act in the same manner as in the form disclosed in Figure 1. 34'' designates a roller and 35'' designates an arm upon which roller 34'' is mounted, and which is rigidly secured to casing 1''. The door opening means disclosed in Figures 1 and 8 may be employed to

open the door when the latch has been released.

In its operation a force is exerted on the knob 20" by the hand of the party. This causes the lug 4" to be moved forward and the roller 5" to move down along the beveled surface swinging lever 6" on its pivot and raising rod 9" thus compressing the spring 11". Roller 34" moves across the flat upper surface of the lug 4". When roller 5" moves to the lowermost position of the lug 4" it encounters the upward beveled surface of the lug and under the action of spring 11" quickly moves across such surface swinging the door outwardly and permitting the door opening means to carry it to open position. The door is closed by pushing or slamming. When the lug 4" engages rollers 5" and 34", the roller 5" is forced down along the first beveled surface of the lug 4" while the roller 34" rides across the upper flat surface of the lug 4". The roller 5" passes on to the lowermost point on lug 4" and then up the oppositely beveled surface of the lug. If there were no roller 34" the lever 6" acting on lug 4" would force the door out of position upwardly and soon render it unfit for closing the fuel opening in casing 1". With such roller acting upon the top of the lug this result is impossible, and after long use little or no wear occurs on the upper surface of the lug and the door is continually maintained in the correct position. The same type of latching means is also employed for securing the ash door in closed position.

Figure 6 discloses a detail showing of the foot lever means for releasing the latch. The foot lever 13 has a slot in its body portion for the reception of a lug on the casing which acts as a pivot. 11 is a spring which is compressed by the upward movement of the rocking lever 13. 12 is a nut for controlling the compression of spring

11 and 14 is a nut for securing an end of lever 13 to rod 9. 10 designates a housing or bracket secured to flange 2 for reception of spring 11.

Having thus described my invention, I claim:

1. In a circulating heater an inner casing forming a combustion chamber, an outer casing spaced from said inner casing, registering openings in said inner and outer casings, a door closing said openings, said door comprising spaced inner and outer portions for closing said respective openings, latch means supported between the inner and outer casing, and cooperating with said inner door portion to normally maintain said door in tight closed position. 5

2. In a circulating heater, an inner casing 15 forming a combustion chamber, an outer casing spaced from said inner casing, registering openings in said inner and outer casings, a door closing said openings, said door comprising spaced 20 inner and outer portions for closing said respective openings, latch means supported between the inner and outer casing and cooperating with said inner door portion to normally maintain said door in tight closed position, and means supported by said stove to release said latch. 25

3. In a circulating heater, an inner casing forming a combustion chamber, an outer casing spaced from said inner casing, registering openings in said inner and outer casings, a door comprising spaced inner and outer portions for closing said 30 respective openings, latch means supported between the inner and outer casing and cooperating with said inner door portion to normally maintain said door in tight closed position, means supported by said stove to release said latch, and 35 spring means supported on said outer casing to bias said door to open position.

GEORGE D. MATTHEWS.
